LATCH-OPEN MECHANISM FOR AIR BLAST CIRCUIT BREAKER

Haakon Forwald, Ludvika, Sweden, assignor to Allmanna Svenska Elektriska Aktiebolaget, Västeras, Sweden, a corporation of Sweden

Filed June 2, 1959, Ser. No. 817,645

Claims priority, application Sweden June 4, 1958
10 Claims. (Cl. 200—148)

This invention relates to a contact latch mechanism for pneumatically operated circuit breakers, and more specifically relates to a latch mechanism which latches the contacts open responsive to a decrease in the air pressure maintaining the contacts open against the force of a closing spring.

Pneumatically operated circuit breakers are well known where a stationary contact is carried in a first housing and the movable contact, and its operating mechanism is carried in a second housing removably connected to the first housing. If desired, the first housing can be under pressure to provide an air blast for extinguishing an arc drawn when the movable contact moves to a disengaged position. The movable contact is normally biased toward an engaged position by a closing spring means, and is moved to the open position and held in the open position by a fluid under pressure, such as air. Although this type of operating mechanism is extremely desirable because of its inherent simplicity and reliability, it is possible that air pressure will be unintentionally lost when the contacts are open, so that the closing spring will move the contacts to their engaged position. This unintentional closing operation can cause severe damage to the breaker and to the components protected thereby, and is a serious hazard to operating personnel working on the protected lines.

Accordingly, latch means have been provided where a physical latch is connected to the movable contact responsive to a predetermined loss of air pressure. This latch mechanism has been connected to the first housing which contains the stationary contact structure so that when the latch is operated, the second housing containing the movable contact and its operating mechanism is physically latched to the first housing. Therefore, it is not possible to remove the second housing from the first housing for inspection and repair.

The principle of the present invention is to provide a latch mechanism which is carried by the second housing containing the movable contact and its operating mechanism so that when the latch operates due to a loss in operating pressure, the housing carrying the latch and the movable contact structure in the latched open position may be removed for inspection and repair of the pneumatic system or associated components which have failed. Furthermore, the latch structure may be constructed to latch the removable contact along its axis whereby the force exerted by the closing spring against the movable contact will not cause rocking or tilting of the movable contact.

Accordingly, the primary object of this invention is to latch the contacts of a pneumatically operated circuit interrupter in the open position responsive to a predetermined loss in operating pressure.

Another object of this invention is to provide a novel latch structure for pneumatically operated circuit breakers wherein the movable contact is latched open upon the failure of air pressure and the housing portion containing the latch may be easily disassembled for repair and maintenance of the mechanism.

A further object of this invention is to provide a latch mechanism for a movable circuit breaker contact which is operated and maintained in the disengaged position by

2

fluid pressure wherein the latch operates responsive to a predetermined loss of air pressure and permits disassembly of the unit.

These and other objects of this invention will become apparent from the following description when taken in connection with the drawings, in which:

FIGURE 1 shows a side cross-sectional view of one embodiment of the novel latch structure of the invention in combination with a pneumatically operated circuit breaker.

FIGURE 2 shows a detailed view of the latch member carried by the movable contact.

Referring now to the drawings, a first housing 10 is normally filled with compressed air derived from a compressed air source 11 which is connected to housing 10 by conduit 12. Conduit 12 has a valve 13 therein for disconnecting housing 10 and source 11. A terminal bushing 14 is connected at the top of housing 10 in sealed relation and is terminated at its lower end by a stationary contact 15 connected at the bottom of the conductor extending through the terminal bushing 14.

A second housing 16 carries the movable contact structure and its operating mechanism and is clamped to the stationary contact housing 10 in any desired manner, as by the bolt means 17. Thus, housing 16 carries a movable nozzle-shaped contact 18 which is connected to a piston means 19 by the connecting rod 20. The connecting rod 20 has an extending portion 21, best seen in FIGURE 2, which is terminated in a bifurcated portion 22 which carries a pin 23, as shown in FIGURE 2. Rod 20 and pin 23 are movable downwardly into engagement with a pawl 24 which is pivotally mounted on pivot 25, and is movable into latching engagement with pin 23. Thus, rod 20 and its pin 23 form the first portion of a latch mechanism, while pawl 24 forms a second and cooperating portion of a latch mechanism.

The pawl 24 is driven by a link 26 which is connected to a piston 27 carried in cylinder 28 and is movable responsive to the pressure in conduit 30 which is connected to conduit 12. A spring 29 biases piston 27 downwardly to move pawl 24 to its latching position, but this motion is normally prevented by the pressure beneath piston 27 from conduit 12. When this pressure fails, however, piston 27 will drop under the influence of spring 29 and pawl 24 will move to its latching position.

The movable contact 18 is normally biased to the engaged position shown in FIGURE 1 by closing spring 31 which is seated beneath piston 19 and biases piston 19 upwardly. In order to move piston 19, and, thus, movable contact 18 to a disengaged position, a valve 32 is movable to connect the upper area 33 adjacent the top of the cylinder containing piston 19 to the pressure of conduit 12 over the conduit 34. The lower surface of piston 19 is connected to the external pressure or atmospheric pressure.

Accordingly, when valve 32 connects conduit 12 to conduit 34, the pressure in volume 33 increases to overcome the spring force of closing spring 31 so that the contacts are driven to their disengaged position.

Although it is not necessary for purposes of the instant invention, the air blast action during contact disengagement may be noted. Prior to opening, the upper end of the movable contact is sealed to the stationary contact in air tight relation. During the opening operation, however, this seal is defeated and the compressed air contained in housing 10 will be forced through the centre of the movable contact and through the arc, and then through check valve means 35. The air blast across the opening contacts is continued until piston 19 drops to close off check valve 35. The movable contact will thereafter be held open by the high pressure of volume 33.

which imparts a greater force to the top of piston 19 than does the spring 31 to the bottom of piston 19.

In order to close the circuit breaker, valve 32 is operated so that conduit 34 is vented to the external air whereby the pressure in volume 33 decreases and the spring force of spring 31 closes the contacts.

In accordance with the present invention, when the movable contact 18 is held in its disengaged position by means of the high pressure in volume 33, the mechanical latch including pawl 24 will be disengaged. When, however, there is a leak, or the pressure of source 11 decreases below a predetermined value so that there may be an unintentional closing of the movable contact, the piston 27 will drop before the spring 31 can drive the contacts closed, whereby pawl 24 will engage pin 23 to latch the contacts open. Thereafter, a complete loss of air pressure will be incapable of closing the movable contact against the latch mechanism. When pressure is returned, the piston 27 will be driven upwardly to release this latching engagement so that normal operation can proceed.

Since the latch mechanism is carried in the movable contact housing, although the movable contact is latched open under low pressure conditions, the housing 16 can be removed from housing 10 so that the mechanism may be inspected and repaired. This is to be contrasted to the previous types of pressure responsive latches wherein the latch mechanism formed a connection between housings, such as housing 10, and the lower housing 16, so that the disconnection of the housings was not possible.

Furthermore, the latch mechanism operates along the axis of the movable contact. Therefore, when contact rod 20 is latched open, it will not be tilted by the force of closing spring 31.

Although the invention has been described with respect to its preferred embodiments it should be understood that many variations and modifications will now be obvious to those skilled in the art, and it is preferred, therefore, that the scope of this invention be limited not by the specific disclosure herein but only by the appended claims.

What is claimed is:

1. A latch mechanism for a pneumatically operated circuit breaker; said pneumatically operated circuit breaker including a first and second housing, said first housing being removably connected to said second housing, said first housing carrying a first contact, said second housing carrying a second contact movable between an engaged and disengaged position with respect to said first contact when said first housing is connected to said second housing, a pneumatic operating means for moving and maintaining said second contact out of engagement with respect to said first contact, a source of air under pressure, connections from such source to said pneumatic operating means and to said first housing, a valve in said connection to said pneumatic operating means, latch means engageable with said movable contact and movable to a latching position to latch said movable contact in said disengaged position, and means operatively connected to said latch means and responsive to a predetermined pressure condition in said compressed air source to move said latch means to latching position upon the drop of pressure in said first housing below a predetermined pressure and to move said latch means to unlatching position upon a rise of pressure in said first housing above said predetermined pressure.

2. A latch mechanism for a pneumatically operated circuit breaker, said pneumatically operated circuit breaker including a first and second housing, said first housing being removably connected to said second housing, said first housing carrying a first contact, said second housing carrying a second contact movable between an engaged and disengaged position with respect to said first contact when said first housing is connected to said second housing, a pneumatic operating means for moving and maintaining said second contact out of engagement with

respect to said first contact, a source of air under pressure, connections from such source to said pneumatic operating means and to said first housing, a valve in said connection to said pneumatic operating means, latch means engageable with said movable contact and movable to a latching position to latch said movable contact in said disengaged position, and means operatively connected to said latch means and responsive to a predetermined pressure condition in said compressed air source to move said latch means to latching position upon the drop of pressure in said first housing below a predetermined pressure and to move said latch means to unlatching position upon a rise of pressure in said first housing above said predetermined pressure, said latch means being carried by said second housing.

3. A latch mechanism for a pneumatically operated circuit breaker, said pneumatically operated circuit breaker including a first and second housing, said first housing being removably connected to said second housing, said first housing carrying a first contact, said second housing carrying a second contact movable between an engaged and disengaged position with respect to said first contact when said first housing is connected to said second housing, a pneumatic operating means for moving and maintaining said second contact out of engagement with respect to said first contact, a source of air under pressure, connections from such source to said pneumatic operating means and to said first housing, a valve in said connection to said pneumatic operating means, latch means engageable with said movable contact and movable to a latching position to latch said movable contact in said disengaged position, and means operatively connected to said latch means and responsive to a predetermined pressure condition in said compressed air source to move said latch means to latching position upon the drop of pressure in said first housing below a predetermined pressure and to move said latch means to unlatching position upon a rise of pressure in said first housing above said predetermined pressure, said latch means being carried by said second housing, said first and second housings being removable when said latch means is in said latching position.

4. A latch mechanism for a pneumatically operated circuit breaker, said pneumatically operated circuit breaker including a first and second housing, said first housing being removably connected to said second housing, said first housing carrying a first contact, said second housing carrying a second contact movable between an engaged and disengaged position with respect to said first contact when said first housing is connected to said second housing, a pneumatic operating means for moving and maintaining said second contact out of engagement with respect to said first contact, a source of air under pressure, connections from such source to said pneumatic operating means and to said first housing, a valve in said connection to said pneumatic operating means, latch means engageable with said movable contact and movable to a latching position to latch said movable contact in said disengaged position, and means operatively connected to said latch means and responsive to a predetermined pressure condition in said compressed air source to move said latch means to latching position upon the drop of pressure in said first housing below a predetermined pressure and to move said latch means to unlatching position upon a rise of pressure in said first housing above said predetermined pressure, said second contact operating means including means for moving said second contact along an axis to said engaged position, said latching means engaging said movable contact along said axis.

5. A latch mechanism for a pneumatically operated circuit breaker, said pneumatically operated circuit breaker including a first and second housing, said first housing being removably connected to said second housing, said first housing carrying a first contact, said second housing carrying a second contact movable between an

engaged and disengaged position with respect to said first contact when said first housing is connected to said second housing, a pneumatic operating means for moving and maintaining said second contact out of engagement with respect to said first contact, a source of air under pressure, connections from such source to said pneumatic operating means and to said first housing, a valve in said connection to said pneumatic operating means, latch means engageable with said movable contact and movable to a latching position to latch said movable contact in said disengaged position, and means operatively connected to said latch means and responsive to a predetermined pressure condition in said compressed air source to move said latch means to latching position upon the drop of pressure in said first housing below a predetermined pressure and to move said latch means to unlatching position upon a rise of pressure in said first housing above said predetermined pressure, said second contact operating means including means for moving said second contact along an axis to said engaged position, said latching means engaging said movable contact along said axis, said latch means being carried by said second housing, said first and second housings being removable when said latch means is in said latching position.

6. In a pneumatically operated circuit breaker, a housing, a relatively stationary contact and a relatively movable contact in said housing, and an operating mechanism for said relatively movable contact, a first operating means for moving said relatively movable contact into engagement with respect to said relatively stationary contact and a second operating means for moving said relatively movable contact to a disengaged position with respect to said relatively stationary contact, said second operating means comprising a piston means operatively connected to said relatively movable contact and pneumatic pressure means for moving said piston, a source of air under pressure, connections from said source to said pneumatic pressure means, a valve in said connection to said pneumatic pressure means, a latch mechanism operatively engageable with said movable contact, said latch mechanism being movable to a latching position to latch said relatively movable contact in said disengaged position, said latch mechanism being operable responsive to variations in the pressure of said pneumatic pressure means to move the latch mechanism to latching position upon the drop of pressure in said compressed air source below a pre-determined air pressure and to move the latch mechanism to unlatching position upon a rise in pressure of said housing above said predetermined pressure.

7. In a pneumatically operated circuit breaker, a housing, a relatively stationary contact and a relatively movable contact in said housing, and an operating mechanism for said relatively movable contact, a first operating means for moving said relatively movable contact into engagement with respect to said relatively stationary contact and a second operating means for moving said relatively movable contact to a disengaged position with respect to said relatively stationary contact, said second operating means comprising a piston means operatively connected to said relatively movable contact and pneumatic pressure means for moving said piston, a source of air under pressure, connections from said source to said pneumatic pressure means, a valve in said connection to said pneumatic pressure means, a latch mechanism operatively engageable with said movable contact, said latch mechanism being movable to a latching position to latch said relatively movable contact in said disengaged position, said latch mechanism being operable responsive to variations in the pressure of said pneumatic pressure means to move the latch mechanism to latching position upon the drop of pressure in said compressed air source below a pre-determined air pressure and to move the

latch mechanism to unlatching position upon a rise in pressure of said housing above said predetermined pressure, said latch mechanism being mounted independently of said relatively movable contact.

5 8. In a pneumatically operated circuit breaker, a housing, a relatively stationary contact and a relatively movable contact in said housing, and an operating mechanism for said relatively movable contact, a first operating means for moving said relatively movable contact into engagement with respect to said relatively stationary contact and a second operating means for moving said relatively movable contact to a disengaged position with respect to said relatively stationary contact, said second operating means comprising a piston means operatively connected to said relatively movable contact and pneumatic pressure means for moving said piston, a source of air under pressure, connections from said source to said pneumatic pressure means, a valve in said connection to said pneumatic pressure means, a latch mechanism operatively engageable with said movable contact, said latch mechanism being movable to a latching position to latch said relatively movable contact in said disengaged position, said latch mechanism being operable responsive to variations in the pressure of said pneumatic pressure means to move the latch mechanism to latching position upon the drop of pressure in said compressed air source below a pre-determined air pressure and to move the latch mechanism to unlatching position upon a rise in pressure of said housing above said predetermined pressure, said latch mechanism being mounted independently of said relatively movable contact, said first operating means comprising spring means engaging said piston means.

35 9. In a pneumatically operated circuit breaker, a housing, a relatively stationary contact and a relatively movable contact in said housing, and an operating mechanism for said relatively movable contact, a first operating means for moving said relatively movable contact into engagement with respect to said relatively stationary contact and a second operating means for moving said relatively movable contact to a disengaged position with respect to said relatively stationary contact, said second operating means comprising a piston means operatively connected to said relatively movable contact and pneumatic pressure means for moving said piston, a source of air under pressure, connections from said source to said pneumatic pressure means, a valve in said connection to said pneumatic pressure means, a latch mechanism operatively engageable with said movable contact, said latch mechanism being movable to a latching position to latch said relatively movable contact in said disengaged position, said latch mechanism being operable responsive to variations in the pressure of said pneumatic pressure means to move the latch mechanism to latching position upon the drop of pressure in said compressed air source below a pre-determined air pressure and to move the latch mechanism to unlatching position upon a rise in pressure of said housing above said predetermined pressure, said operative connection between said relatively movable contact and said piston including rod means having a portion extending through said piston means, said latch means engaging said extending portion of said rod means at a point along its axis.

65 10. In a pneumatically operated circuit breaker, a housing, a relatively stationary contact and a relatively movable contact in said housing, and an operating mechanism for said relatively movable contact, a first operating means for moving said relatively movable contact into engagement with respect to said relatively stationary contact and a second operating means for moving said relatively movable contact to a disengaged position with respect to said relatively stationary contact, said second operating means comprising a piston means operatively connected to said relatively movable contact and pneu-

matic pressure means for moving said piston, a source of air under pressure, connections from said source to said pneumatic pressure means, a valve in said connection to said pneumatic pressure means, a latch mechanism operatively engageable with said movable contact, said latch mechanism being movable to a latching position to latch said relatively movable contact in said disengaged position, said latch mechanism being operable responsive to variations in the pressure of said pneumatic pressure means to move the latch mechanism to latching position 10 upon the drop of pressure in said compressed air source below a pre-determined air pressure and to move the latch mechanism to unlatching position upon a rise in pressure of said housing above said predetermined pressure, said operative connection between said relatively movable contact and said piston including rod means having a portion extending through said piston means, said latch means engaging said extending portion of said rod means at a point along its axis, said latch mechanism being 15

mounted independently of said relatively movable contact.
